Attorney

UNITED STATES PATENT OFFICE.

LEWIS KNIGHT, OF PLAINVIEW, TEXAS.

AEROPLANE TOY.

Application filed June 30, 1926. Serial No. 119,640.

This invention relates to toys of the aero-plane type and has for its primary object to provide a toy of a construction generally similar to a conventional aeroplane, together with means for facilitating the movement thereof, representative of the general movement of a real aeroplane while in flight.

Other objects will become apparent as the nature of the invention is better understood, the same comprising the novel form, combination and arrangement of parts hereinafter more fully described, shown in the accompanying drawings and claimed.

In the drawing, wherein like reference characters designate corresponding parts throughout the same:

Figure 1 is a side elevation of a toy constructed in accordance with the present invention, the same being disclosed as simulating the general movement of a real aeroplane when in flight, and

Figure 2 is a detail longitudinal section thereof.

Now having particular reference to the drawing, my novel toy embodies the provision of a miniature aeroplane 5, constructed of suitable material, through the fuselage or body portion of which is a longitudinal bore 6, the front end of which is enlarged for receiving one end of a metallic sleeve 7, the outer end of which is flared and provided upon its top side with an eye member 8. Arranged rigidly or for rotation upon the projecting end of this sleeve is a miniature propeller 9, while attached to the eye is one end of a string 10 of predetermined length. This string is directed through the sleeve 7 and through the bore 6 of the fuselage or body of the miniature aeroplane, and is equipped at its opposite end with a pull ring 11.

Attached to the string 10 between the eye 8 and sleeve 7 is an eye screw 12 for permitting of the loose attachment of the string to a supporting post or wall A.

In use, the string is pulled forwardly through the bore 6 of the aeroplane fuselage or body until the pull ring 11 strikes against the rear end thereof, this action being prior to or subsequent to the attachment of the eye screw to the post or wall. The miniature

aeroplane is then carried away from the post or wall to the limit of its movement after which a continuous pull is exerted upon the ring 11 for obviously drawing the string through the bore of the body or fuselage which will propel the aeroplane toward the supporting post or wall in simulation of a flight of an actual aeroplane.

The provision of a toy of this character will be highly amusing to children and will also assist in instructing children or even grownups in the aeroplane field.

Having thus described my invention, what I claim as new and desire to secure by Letters Patent is:

1. In a toy of the character described, a miniature aeroplane having a continuous longitudinal bore through the body thereof, a string attached at one end to the body at the forward end of said bore, and being extended rearwardly through the bore, and means for loosely attaching the string between its anchored end and the front end of the bore to a support.

2. In a toy of the character described, a miniature aeroplane, having a continuous longitudinal bore through the body thereof, a sleeve arranged within the front end of the bore, a string attached at one end to the projecting end of the sleeve and being extended rearwardly through the bore, and means for loosely attaching the string between its anchored end and the front end of the bore to a support.

3. In combination, an eye member attached to a support, a miniature aeroplane having a continuous longitudinal bore through the body thereof, a sleeve arranged within the front end of the bore, a string attached at one end to the projecting end of the sleeve, said string being passed through the aforementioned eye member and extending rearwardly through the longitudinal bore of the aeroplane, said aeroplane being adapted to move forwardly along the string toward the eye member when the rear end of the string is pulled.

In testimony whereof I affix my signature.

LEWIS KNIGHT.
